(57) **CLAIM**

The ornamental design for a fuel dispenser, as shown and described.

DESCRIPTION

FIG. 1 is a front perspective view of a fuel dispenser, showing the new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top view thereof; and,

FIG. 7 is a bottom view thereof.

In the drawings, the broken lines depict portions of the fuel dispenser that form no part of the claimed design.
